UNITED STATES PATENT OFFICE.

WILLIAM B. BROTHERS, OF ILLIOPOLIS, ILLINOIS.

ROAD-WORKING MACHINE.

No. 886,182.

Specification of Letters Patent.

Patented April 28, 1908.

Application filed May 3, 1907. Serial No. 371,704.

To all whom it may concern:

Be it known that I, WILLIAM B. BROTHERS, a citizen of the United States, residing at Illiopolis, in the county of Sangamon and 5 State of Illinois, have invented new and useful Improvements in Road - Working Machines, of which the following is a specification.

This invention relates to a road working 10 machine and more particularly to a scraper for grading new or old roads.

The invention has for one of its objects to improve and simplify the construction and operation of an apparatus of this character 15 so as to be comparatively easy and inexpensive to manufacture and thoroughly reliable and efficient in use.

A further object of the invention is the provision of a road scraper in which the blade or 20 blades can be readily adjusted to throw the sand, mud or other material of the road to the right or left, there being means for changing the set of the blade or blades.

Another object is the employment of a pair 25 of parallel blades connected with a platform extending between them, which together with the blades, can be adjusted to any desired angle to the line of travel for permitting the material to be thrown toward the 30 center of the road from the right or left, the blades being provided with devices for independently adjusting them.

With these objects in view and others as will appear as the description proceeds, the 35 invention comprises the various novel features of construction and arrangement of parts which will be more fully described hereinafter and set forth with particularity in the claims appended hereto.

40 In the accompanying drawing which illustrates one of the embodiments of the invention, the figure is a perspective view of the improved road working machine.

Referring to the drawing, 1 designates a 45 flat platform extending the full width of the machine and secured thereto is a central beam 2. Extending parallel with the platform and under the beam 2 are scrapers 3 which may be in the form of beams of iron 50 or wood like the parts 1 and 2 and provided with removable blades 4 extending the full width of the machine. The ends of the scrapers 3 are connected by links 5 with the ends of the platform 1, there being provided 55 clips or similar fasteners 6 bolted or other-

wise secured to the platform 1 and thus bracing the scrapers on the platform. The scrapers are suspended adjacent their centers on independent levers 8 fulcrumed, at 9, respectively on the front and rear end of the center beam 2, there being toothed sectors 10 on the beam and latches 11 co-operating therewith, whereby the scrapers can be set at any desired angle in respect to the vertical plane. The pivots 9 are horizontal so that by actuating the levers 8, the blades can be inclined forward or rearward as desired. On the platform 1 is arranged a driver's seat 12 from which the levers 8 are within convenient reach of the driver so that he can adjust the scrapers with facility.

The apparatus is provided with a tongue 13 disposed directly in line with the central beam 2 and hingedly connected at 14 with the center of the front scraper and attached to the tongue or pole 13 is a double-tree 15 whereby the machine can be drawn by horses. Extending from the double-tree is a brace rod 16 that is bowed and has its ends 17 hingedly connected with the terminal portions of the front scraper 3. The middle portion of the brace rod is provided with a series of apertures 18 arranged in the arc of a circle and in any one of these apertures is engaged a pin 19 that extends vertically through the tongue 13, there being a plate 20 under the tongue for receiving the bottom end of the pin and between which and the under surface of the tongue the flattened apertured portion 21 of the brace rod is slidably held. As shown in the present instance, the pin passes through the central aperture so that the scrapers are held at right angle to the direction of travel of the machine. By removing the pin and swinging the tongue in any of the other apertures, the scrapers will assume a position inclined to the direction of travel of the machine so that the surface material of the road can be thrown to the right or left, as desired.

100 From the foregoing description taken in connection with the accompanying drawing, the advantages of the construction and of the method of operation will be readily apparent to those skilled in the art to which the invention appertains, and while I have described the principles of operation of the invention, together with the apparatus which I now consider to be the best embodiment thereof, I desire to have it understood that 105 110

the apparatus shown is merely illustrative and that various changes may be made when desired as are within the scope of the claims.

Having thus described the invention, what I claim as new is:

5. 1. In a road working machine, the combination of a pair of surface working elements disposed parallel, a platform, a cross beam at the center of the platform, adjusting levers 10 mounted on the beam and connected with the elements for independently inclining the elements to a vertical plane, connections between the ends of the elements and platform arranged to permit the elements to tilt, a 15 tongue flexibly connected with the front element, a bowed bar connected with the ends of the front element and extending forwardly therefrom, and means for connecting the tongue with the bar.
20. 2. In a road working machine, the combination of a frame, parallel surface working elements, levers fulcrumed on the frame to swing in a vertical plane on horizontal pivots and rigidly connected with the elements at 25 the front thereof for tilting the same, and means for bracing the ends of the elements on the frame, a draft member flexibly connected with the front element, a bowed rod

connected with the front element and extending forwardly therefrom and connected 30 with the tongue.

3. In a road working machine, the combination of a platform, a cross beam at the middle thereof, surface working elements arranged in front and behind the platform, adjusting levers mounted on the beam and connected with the elements for tilting the same, links between the ends of the platform and elements, pivots on the ends of the elements and to which the links are connected, a draft 40 device connected entirely with the front element.

4. In a road working machine, the combination of a frame, surface working elements thereon, means for tilting the elements independently and holding them in adjusted position, a tongue flexibly connected at its rear end to the front element, and connecting means between the tongue and the extremities of the front element.

In testimony whereof, I affix my signature in presence of two witnesses.

WILLIAM B. BROTHERS.
